UNITED STATES PATENT OFFICE.

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK.

LOOSE-LEAF BINDER.

Application filed February 24, 1920. Serial No. 360,712.

To all whom it may concern:

Be it known that I, CLARENCE D. TRUSSELL, a citizen of the United States of America, residing in Poughkeepsie, in the county 5 of Dutchess and State of New York, have invented certain new and useful Improvements in Loose-Leaf Binders, of which the following is a specification.

This invention relates to temporary binders or those designed for binding together 10 loose leaves in book form. It relates particularly to so-called ring binders, wherein half rings or hooks are adapted to close together to constitute binding means and to 15 open out to permit the removal of the perforated leaves.

The improvement relates to means for opening the half rings or hooks, to permit 20 the removal of the perforated leaves, where- 25 by a lever shaped opening device is em- ployed.

Referring to the accompanying drawings 30 wherein one form of such device is illus- trated,

Figure 1 is a perspective view of a section 35 of a loose-leaf binder showing the improved construction,

Fig. 2 is a sectional view of the binding 40 device and the opening means,

Fig. 3 is a cross section on line 3-3 of 45 Fig. 2 showing one set of hooks and the opening means,

Fig. 4 is a top view of the binding device 50 with the cover plate removed; and

Fig. 5 is a cross section on line 5-5 of 55 Fig. 2 showing the hooks closed.

Fig. 6 shows the blank or stamping from 60 which the opener is formed;

Fig. 7 shows in plan one end of the back 65 plate E;

Fig. 8 is a transverse section of the back 70 and cover plates on the line 8-8 in Fig. 7;

Fig. 9 is a plan of the opener in its pre- 75 ferred construction, showing in dotted lines 80 the blank from which it is bent up;

Fig. 10 is a side elevation of the opener 85 shown in Fig. 9;

Fig. 11 is a transverse section thereof on 90 the line 11-11 in Fig. 10.

In the drawings, A designates the cover 95 of a loose-leaf binder, and B, B the half rings or hooks for holding the paper. C is 100 a cover plate having transverse notches b b designed to receive the hooks B B and a 105 longitudinal slot c designed to receive the

opening means and hold it in place. D represents the opening means as a whole. E is a back plate of the usual construction for holding the hook plates, having its edges turned in as at l l and with portions near 110 one end struck up to form projections d d. The plate E is commonly resilient, serving as the spring for holding the hooks open or closed, but this feature is not essential to the present invention. F F are plates carrying the hooks B B and held in the plate E. The plates F F interlock with one another in any known way, as by means of a tongue and groove on projections f f; and may have outer projections e e which are 115 adapted to fit under the turned in edges l l of the plate E to constitute a rocking bearing.

The opener D consists of a single metal piece, or lever, with a button or thumb piece 120 G. The part D is notched at its forward end to form a toe or lever-arm a and is notched at its rear portion to form a stop finger h to engage the under side of the cover plate C to hold it in place. The under face of the 125 part D is formed as a fulcrum or rocking bearing H. The part D projects through slot c and is held in position laterally by this slot and by the two projections d d, as shown in Fig. 5. The lever arm a projects under the plates F F and in contact therewith. As the opener projects up through the slot c instead of out through the end of the binder, the down-turned ends of the 130 cover plate C are allowed to completely cover 135 the binding mechanism, no part of which is exposed.

In operation, when the button G is depressed, the opener is tilted to the position 140 shown in dotted lines in Fig. 2, so that by 145 rocking on its lower edge H, its toe a is lifted, which presses upward on the plates F F forcing them outward, and thus opening the hooks B B. The plates F F being 150 spring pressed by the back plate E, will remain in this open position until forced back to the original position by closing the hooks B B. The finger h abuts against the cover plate C and retains the opener D within said 155 plate.

The opener D requires only a very slight 160 downward pressure to be exerted on the button G, in order to open the hooks, thus forming a very simple and easily operated 165 opening means.

The opener D is of simple construction, being stamped from a metal blank by a single operation. The button G may be made integral therewith and connected by a narrow neck k.

The whole device may be best made by first punching out a blank as shown in Fig. 6, and then by one or more operations swaging down the portion m to form the thumb-piece or button G.

A further development of the invention is shown in Figs. 9, 10 and 11, wherein the opener D is made of two thicknesses of metal r' r' which have a tendency to spring slightly apart as shown in Fig. 9 or Fig. 11. This is best formed by bending up a single blank or punching which may have the shape shown in dotted lines in Fig. 9. Fig. 11 shows how the metal is folded together at the neck portion k'. In other respects the construction is the same as that before described, as is seen in Fig. 10. This construction is especially adapted for the larger sizes of books for which a large thumb-piece is desirable, as it enables this to be formed of the requisite strength without requiring a swaging operation such as that described above. It has an important advantage in that since the two plates or leaves r' r' tend to spring apart, they make a close engagement with the guiding faces of the bent up projections d, thus avoiding any looseness or rattling, and may also make a similar engagement with the faces of the slot c. In putting the opener in place, the two tongues r' r' are pressed together so that this spring tension is thus utilized. When thus together they function as one piece and the operation is indistinguishable from that of the construction first described except for such freedom from looseness and rattling.

With either construction it is advantageous that the metal of the opener is used edgewise, the movement being in the plane of the metal, thus reducing liability of bending it in use.

Since the opener D is held in position by the top plate C, it is desirable to insure against this plate being displaced at the end or pried apart from the spring plate E, in order that the means for guiding the opener be not brought out of operative relation therewith. This is accomplished most effectually by clinching the plates C and E together near one or both ends, but especially adjacent to the guiding surfaces of the opener. This construction is shown in Figs. 7 and 8, wherein the portions p p of the flange on the plate C are bent or swaged inwardly to embrace a portion of the plate E. To facilitate this, the plate E is best formed with slots or notches q q on opposite sides, into which the portions p are pressed. By this means the two plates are firmly locked together at their ends.

The invention may be modified or varied in certain respects other than herein specifically described.

What I claim is:—

1. A loose-leaf binder comprising hook plates having hooks, a back plate, and an opener for said hooks comprising a flat metal plate, the plane of which coincides with the longitudinal medial plane of the binder, said plate movable in its own plane, having a toe engaging beneath the hook plates, and having on its lower edge a rocking fulcrum bearing against said back plate, and the binder formed with lateral guides for holding the opener in said plane. 70

2. A loose leaf binder comprising a back plate, hook plates having hooks, and a cover plate, said cover plate having a longitudinal slot and an opening means movable in said slot. 80

3. A loose leaf binder comprising hook plates, a back plate and a cover plate, with an opener consisting of a flat plate mounted in a longitudinal plane, having a rocker bearing on the back plate, a toe engaging the hook plates, and an operating arm projecting through a slot in the cover plate. 90

4. A loose leaf binder comprising hook plates, a back plate and a cover plate, with an opener consisting of a flat plate mounted in a longitudinal plane, having a rocker bearing on the back plate, a toe engaging the hook plates, an operating arm projecting through a slot in the cover plate, and a stop adapted to bear under said cover plate. 95

5. A loose leaf binder having hook plates, and a top plate, combined with an opener formed as a rocking piece of flat plate metal, located and moving in a longitudinal plane transverse to the hook plates, having a toe engaging beneath the hook plates, said opener plate having a thumb piece in a plane transverse to that of the plate, the top plate having guiding means for the opener, and the thumb-piece of the latter projecting above the top plate. 105

6. A loose-leaf binder comprising hook plates, a back plate and a cover plate with an opener of plate metal in a longitudinal plane transverse to the hook plates, having portions lying between and engaged by said back plate and cover plate. 115

7. An opener for a loose leaf binder formed of flat plate metal folded to form two leaves, with a thumb piece in a plane transverse to that of the plate. 120

8. An opener for a loose leaf binder formed of flat plate metal in two thicknesses, constituting tongues which tend to press slightly apart. 125

9. A loose leaf binder comprising hook plates having hooks, an opener therefor consisting of a plate movable in its own plane, and a plate engaged by said hook plates and guiding said opener, the opener 130

having resilient engagement therewith to prevent rattling.

10. A loose leaf binder comprising hook plates, a cover plate and an opener, the cover plate having guiding faces for said opener, and the opener formed of plate metal in two thicknesses constituting leaves tending to open slightly apart and thereby press against such guiding faces to avoid rattling.

11. An opener for a loose leaf binder consisting of a flat plate movable in its own plane, being formed of plate metal folded together to constitute two leaves or tongues.

15. 12. A loose leaf binder comprising hook plates, a back plate and a cover plate with an opener engaging and guided by faces formed on the binder, the back plate and cover plate being locked together near their ends adjacent said opener.

20. 13. A loose leaf binder comprising hook

plates, a back plate, and a cover plate, with an opener engaging and guided by said back plate and cover plate, the back plate and cover plate being locked together near their 25 ends adjacent said opener.

14. A loose leaf binder comprising hook plates, a back plate and a cover plate, the back plate having notches and the cover plate having ears bent into said notches 30 for locking said plates together.

15. A loose-leaf binder comprising mating hooks and a resilient mounting therefor, and means for forcing open the hooks, comprising a plate movable in its own plane 35 for opening the hooks, rigid in said plane and having lateral resilient engagement with its mounting adapted to take up looseness and prevent rattling.

In witness whereof, I have hereunto 40 signed my name.

CLARENCE D. TRUSSELL.
